Primary Examiner — Susan Bennett Hattan*Assistant Examiner* — Marie Fast Horse(57) **CLAIM**

The ornamental design for a ceiling fan with light, as shown and described.

DESCRIPTION

FIG. 1 is a perspective view thereof;

FIG. 2 is a front elevational view thereof;

FIG. 3 is a right side view, the left side view thereof being a mirror image;

FIG. 4 is a top plan view thereof; and,

FIG. 5 is a bottom plan view thereof.

The broken lines in the drawings depict parts of the ceiling fan with light that form no part of the claimed design.
